UNITED STATES PATENT OFFICE.

WILLIS F. WALKER, OF SIESHOLTZVILLE, PENNSYLVANIA.

RAIL-FASTENER.

1,314,918.

Specification of Letters Patent.

Patented Sept. 2, 1919.

Application filed January 11, 1919. Serial No. 270,695.

To all whom it may concern:

Be it known that I, WILLIS F. WALKER, a citizen of the United States, residing at Siesholtzville, in the county of Berks and 5 State of Pennsylvania, have invented a new and useful Rail-Fastener, of which the following is a specification.

The device forming the subject matter of this application is a fastener for railroad 10 rails, and one object of the invention is to provide novel means whereby the rails, although held securely in the ordinary sense of the word, will be permitted to have the necessary wave-like movement responsive to 15 passing trains.

Another object of the invention is to provide novel means whereby, if desired, an insulating strip may be held in place with respect to the base flange of the rail.

20 A still further object of the invention is to provide means whereby the rail will be held securely to the tie, to avoid accidents resulting from a separation of the rail from the tie, due to the breaking of securing de- 25 vices, or other causes.

Within the scope of what is claimed, a mechanic may make changes without departing from the spirit of the invention, or placing the utility thereof in jeopardy.

30 In the accompanying drawings:

Figure 1 shows in elevation, a device embodying one form of the invention;

Fig. 2 is a top plan of the structure shown in Fig. 1;

35 Fig. 3 is a cross section on the line 3—3 of Fig. 1;

Fig. 4 is a perspective delineating the keeper;

Fig. 5 is an elevation disclosing a modified form of the invention;

Fig. 6 is a side elevation of the structure shown in Fig. 5;

Fig. 7 is a perspective depicting the retainer;

45 Fig. 8 is a sectional detail illustrating the retainer in relation to other parts of the structure;

Fig. 9 is an elevation disclosing a modification.

50 Referring to Figs. 1, 2, 3, 4, 7, and 8, there is shown a tie 1 which may embody a pair of I-members 2 which may carry plates 3. The tie need not be described in great detail, because it may be of any form, 55 and because a specific tie cannot be covered

in the same application with a rail fastener. One of the I-members 2 and its plate 3 are supplied with openings 4 and 5, spaced apart, the other I-member and its plate being provided with openings 6 and 7, indicated in dotted line in Fig. 1, and spaced apart, the openings 5 and 7 lying between the openings 4 and 6. 60

Strips 8 of insulating material rest on the I-members 2, the base-flange of a rail 65 9 resting on the insulating strips. If a pair of rail ends are to be joined, the same are united by angle bars 10 and bolts 20, as usual. The ends of the insulating strips 8 are overlapped as shown at 11 on the outwardly projecting portions of the angle bars 10 and are received within keepers 12, which, broadly stated, are U-shape in cross section, the keepers being supported on the parts 2 of the tie 1. Each keeper comprises 70 a body portion 14, an upper flange 15 and a lower flange 16, having a notch 17 which receives the member 2 of the tie and prevents the keeper from moving endwise. 75

Retainers 21 are supplied, and rest on 80 the parts 2 of the tie 1, the retainers having inner lugs 22 and outer lugs 23, which, engaging the lateral edges of the parts 2, aid in holding the retainers on the tie. Each retainer has an inwardly extended flange 85 24 which is downwardly convexed as shown at 25, to bear upon the flange 15 of the keeper 12. Openings 26 are formed in the retainers 21 and lead to concaved seats 27. Securing devices, such as U-bolts 28 are 90 mounted in the openings 6 and 4 of the parts 2 of the tie 1 and extend through the openings 26 and the seats 27 in the retainers 21. Nuts 29 are threaded on the bolts and are supplied with rounded ends 30 coacting 95 with the concaved seats 27.

Since the flanges 24 of the retainers 21 are downwardly convexed as shown at 25, the retainers will have a certain amount of spring, giving them a secure hold, under 100 the action of the U-bolts 28. Further, owing to the convexity of the flanges of the retainers, coupled with the fact that the rounded ends 30 of the nuts 29 are received in the concaved seats 27, the rail 9 can have 105 the necessary wave-like motion with respect to the tie, it being a matter of common knowledge that metal ties heretofore have been rejected in practice, for the reason that, in combination with known fasteners, 110

they do not permit the aforesaid motion under the action of the rolling stock.

The retainers 21 and the keepers 12 serve to retain the insulating strips 8 in place, should the strips be used, although, as will be made manifest hereinafter, the insulating strips may be omitted.

In case the fastener is used between the ends of a rail, the angle bars 10 are not employed. Then the U-bolt 28 which, in Fig. 1, is engaged with the opening 4 in one I-member 2 may be shifted to the opening 7 in the other I-member, the other U-bolt being shifted from the opening 6 to the opening 5. In this way, the flanges 24 of the retainers 21 may be caused to coöperate with the base flange of the rail 9, the keepers 12 being shifted inwardly, and the parts 11 of the insulating strips 8 being altered accordingly, to coöperate with the base flange of the rail 9.

In Figs. 5 and 6, parts hereinbefore described are designated by numerals previously used, with the suffix "a." The rail 1^a is of T-form and constitutes a tie, replacing the two members 2 of the tie 1 of Fig. 1. The ends 11^a of a single insulating strip 8^a replace and correspond to the ends 11 of the strips 8 of Fig. 1. Figs. 5 and 6 disclose the application of the invention to a light track of the sort commonly used in mines, and render it evident that the fastener may be used with practically any weight and size of rail.

In Fig. 9, parts hereinbefore described are designated by numerals previously used, with the suffix "b." In this form of the invention, the rail 9^b rests directly on the tie 1^b, the insulating strips and the keeper of Fig. 4 being omitted, the flange 24^b of the retainer 21^b coacting directly with the base flange of the rail 9^b. It will be clear from Fig. 9 that, in all forms of the invention, the insulating strip and the keeper may be left out, should occasion demand, the advantages incident to the convexing of the retainer 21 at 25 and incident to the structure shown in Fig. 8 remaining, nevertheless.

I claim:

1. In a device of the class described, a tie; a retainer on the tie and comprising an inwardly extended flange which is downwardly convexed transversely of the tie to cause the retainer to be supported intermediate its ends and to give the ends of the retainer a vertical spring, and to permit the retainer to have a rocker-like movement under the action of rolling stock; and securing

means engaged with the tie, and with the retainer, adjacent to its ends.

2. In a device of the class described, a tie; a retainer on the tie and comprising an inwardly extended flange which is downwardly convexed transversely of the tie; a keeper of U-shape in cross section disposed beneath the flange and having a notch receiving the tie; and securing means engaged with the tie, and with the retainer adjacent to its ends.

3. In a device of the class described, a tie; a retainer on the tie and comprising an inwardly extended flange which is downwardly convexed transversely of the tie; a keeper of U-shape in cross section disposed beneath the flange and having a notch receiving the tie; an insulating strip on the tie and fitting within the keeper; and securing means engaged with the tie, and with the retainer adjacent to its ends.

4. In a device of the class described, a tie; a retainer on the tie and comprising an inwardly extended flange, the retainer having side lugs coacting with the tie; a keeper of U-shape in cross section disposed beneath the flange and having a notch receiving the tie; an insulating strip on the tie and fitting within the keeper; and securing means engaged with the tie, and with the retainer.

5. In a device of the class described, a tie; a retainer on the tie and comprising an inwardly extended flange which is downwardly convexed transversely of the tie, the retainer being provided with concaved sockets; a U-bolt engaged with the tie and passing through the sockets; and nuts on the U-bolt, the nuts including rounded ends co-operating with the sockets.

6. In a device of the class described, a tie; a rail thereon; angle bars coacting with the rail; retainers on the tie and having flanges overhanging the angle bars; and securing devices engaging the retainers and the tie, the tie having openings receiving the securing devices, the openings being duplicated to permit a shifting of the securing devices, and to permit a coöperation between the retainers and the rail when the angle bars are omitted.

In testimony that I claim the foregoing as my own, I have hereto affixed my signature in the presence of two witnesses.

WILLIS F. WALKER.
